9 Claims. (Cl. 242—45)

1

This invention relates to methods of and apparatus for uniformly tensioning an advancing strand, and more particularly to methods of and apparatus for maintaining constant tension on a wire during the takeup operation of a wire drawing machine.

In the operation of modern high speed wire drawing machines used in the manufacture of fine wire, the wire emerging from the wire drawing machine is usually wound on a suitable reel for further processing operations. This operation is generally referred to as the takeup operation and presents a peculiar problem in that while the wire to be wound on the takeup reel is emerging from the wire drawing machine at a constant rate of speed, the winding diameter of the takeup reel is constantly increasing tending to increase the linear speed of the wire which results in an increased tension on the wire.

However, as constant tension must be maintained on the wire emerging from the wire drawing machine during the takeup operation, it has been the practice in the past in some instances to operate the takeup reel motor slightly above and slightly below the speed required to takeup the wire emerging from the machine and to control the torque of the motor between two selected points of operation by the actual tension being exerted on the wire. This type of operation places a decreased tension on the wire for a short interval and then an increased tension on the wire for a short interval, which alternating procedure is carried out during the entire takeup operation from an empty reel to a full reel. Obviously, when fine wire is involved, this principle of maintaining an average predetermined tension on the wire is objectionable because each changeover from low tension to high tension produces alternately loosely wound and tightly wound layers on the reel. The tight convolutions pull down into the loosely wound sections, producing a reel of wire from which it is very difficult to unwind the wire, thereby rendering the reel of wire unfit for use with high speed insulating machines, or the like.

An object of the invention is to provide new and improved methods of and apparatus for uniformly tensioning an advancing strand.

A further object of the present invention is to provide new and improved methods of and apparatus for maintaining a constant tension on a wire during the takeup operation of a wire drawing machine.

In accordance with one device embodying features of the invention, a plurality of pulleys are

2

arranged to form an adjustable loop in the wire being advanced from a constant speed wire drawing machine to a variable speed takeup reel. The pulley forming the bottom of the loop is supported only by the wire and is free to travel up or down as the loop contracts or enlarges and is weighted to produce a desired tension on the wire. Means operable by the weighted pulley upon contraction or expansion of the adjustable loop alternately

5 decreases and increases the torque and consequently the speed of the takeup reel motor in accordance with the linear speed differential existing in the wire at the machine and the takeup reel.

The torque of the takeup reel motor is varied 10 between selected limits, in accordance with the present method, by causing the weighted pulley to vary the input voltage to the motor, thereby causing the motor to operate on either of two preselected speed-torque curves. When the

15 motor is operating on the lower speed-torque curve, the torque developed thereby is overcome by the weight carried by the pulley thereby reducing the speed of the motor so that the takeup speed of the wire is less than its supply speed.

20 This operating condition allows the adjustable loop to enlarge to a predetermined size upon the happening of which the weighted pulley causes an increased potential to be supplied to the motor. The motor now operates on a higher speed-torque

25 curve, where the torque of the motor overcomes the weight carried by the pulley, and the takeup speed of the wire is greater than its supply speed. This operation is alternately repeated until the takeup operation on the wire is completed.

30 A complete understanding of the invention will be had from the following detailed description of one embodiment thereof, when read in conjunction with the appended drawing, in which:

35 Fig. 1 shows diagrammatically a wire drawing apparatus and its takeup reel motor together with an electrical control circuit for the takeup reel motor, and

40 Fig. 2 shows diagrammatically the various speed-torque curves of the takeup reel motor obtainable upon the application of various input potentials to the motor.

45 Referring to Fig. 1 of the drawing, a reel 10 contains a supply of relatively coarse wire 11, which is withdrawn therefrom and passed 50 through a suitably mounted bell-shaped guide 12. The guide 12 directs the wire 11 to the first idler pulley of a bank of pulleys 13 forming part of a wire drawing apparatus, indicated generally at 14. The wire 11 passes around the first pulley 13 55 through the first wire drawing die provided in a

die block 15 and thence to the first step of a multi-step capstan 16 mounted on a shaft 17 and driven at a constant rate of speed by a motor 20 connected therewith. After passing several times around the first step of the capstan 16, the wire passes back to the second pulley in the bank 13, through a second die provided in the die block 15 and thence to the second step of the capstan 16, and so on, back and forth between the pulleys 13-13 and the capstan 16 until the wire has 10 passed through each die of the die block 15 and is engaged by the last step of the capstan 16.

When the motor 20 is energized, in a manner hereinafter to be described, the capstan 16 of the wire drawing machine 14 serves to draw the wire 11 through each die in the die block 15, and the dies substantially reduce the diameter of the wire 11 to produce a relatively fine wire indicated by the numeral 21. The wire 21 after passing several times around the last step of the capstan 16 is directed to a guide pulley 22 suitably mounted on a support indicated generally at 23.

The wire 21 passes around the pulley 22 and under a pulley 24 supported only by the wire 21 and slidably positioned in a groove 25 provided in the support 23 and then to a pulley 26 rotatably mounted on the end of an arm 27 pivotally mounted on the support 23. The arm 27 is resiliently supported in a substantially horizontal position by means of a spring 28. The wire 21 passes over the pulley 26 and is engaged by a suitable traversing mechanism 30 which serves to distribute the wire 21 evenly across the winding surface of a takeup reel 31 mounted on a shaft 32 and driven by an induction motor 33.

The arrangement of the pulleys 22, 24 and 26 (Fig. 1) serves to form an adjustable loop in the wire 21 as it advances from the final step of the capstan 16 to the takeup reel 31. The wire 21 is being delivered by the capstan 16 to the adjustable loop formed by these pulleys at a constant rate of speed. Due to the fact that the winding diameter of the takeup reel 31 is constantly increasing as the takeup operation of the wire 21 proceeds from an empty reel to a full reel, the linear speed of the wire 21 at the reel will, after a few layers of wire are wound on the reel, exceed the linear speed of the wire 21 as it leaves the capstan 16. The adjustable loop formed by the pulleys 22, 24 and 26 permits the takeup reel 31 to alternately take up the wire 21 at a rate faster than it is being delivered by the capstan 16 and at a rate lower than it is being delivered by the capstan. The loop is alternately contracted and expanded to such an extent that the movable pulley 24 supported by the loop and riding in the groove 25 actuates suitable control mechanism to effect a change in the input potential applied to the motor 33 in a manner hereinafter to be described.

A weight 34 (Fig. 1) rests on the pulley 24 for the purpose of exerting a predetermined tension on the wire 21 between the capstan 16 and the takeup reel 31, regardless of the position of the pulley 24 in the groove 25. The spring 28 is arranged to hold the arm 27 in a normally horizontal position and is so designed that the arm will remain in that position when the adjustable loop is tensioned by the weight 34 positioned on the pulley 24. The purpose of the spring 28 is to cushion the slight tension variations which occur in the wire 21 due to the winding of the wire on the takeup reel 31 from layer to layer. A pair of spaced arms 35 and 36 are mounted pivotally on the support 23 so that one end of each

of the arms extends into the path of travel of the movable pulley 24. Each of the arms 35 and 36 has the opposite end thereof pivotally secured to the end of a trip arm 37, which is provided with an upper ear 40 and a lower ear 41. A sensitive toggle switch 42 is mounted on the support 23 so that the end of its operating arm 43 is positioned between the ears 40 and 41 provided on the arm 37.

The trip arm 37 is raised and lowered alternately by the pulley 24 as the wire loop is contracted and expanded, thereby actuating the arm 43 of the switch 42, so that it alternately bridges a pair of upper contacts 44 and 45 and a pair of lower contacts 46 and 47. The contacts 44 and 46 are connected together and to a suitable electric controller indicated generally at 50 by means of a conductor 51. The conductor 51 is connected to one side of a suitable potential supply controlled by the apparatus included in the controller 50.

The contact 45 of the switch 42 is connected to one terminal of a coil 52, and the contact 47 is connected to one terminal of a coil 53 of a three-pole, double throw magnetic contactor indicated generally by the numeral 54. The opposite terminals of the coils 52 and 53 are connected together and to the control apparatus 50 by means of a conductor 55. The conductor 55 is connected to the opposite side of the potential supply to which the contacts 42 and 46 of the switch 42 are connected by the conductor 51. Therefore, when the contacts 44 and 45 or the contacts 46 and 47 of the switch are bridged by the arm 43, the corresponding coil 52 or 53 of the contactor 54 is connected across a suitable potential supply emanating from the controller 50.

A three-phase potential supplied from a suitable source (not shown) is directed to the controller 50 by a three-pole switch 56. This three-phase potential is directed by the controller 50 to the constant speed wire drawing motor 20 and to the takeup reel motor 33 through a Y-connected autotransformer 57 and suitable contacts provided on the contactor 54. The control apparatus 50 may be of the type disclosed in C. O. Haase Patent 2,266,861, issued December 23, 1941, or may be of any other suitable type which will cause the motors 20 and 33 to operate in the manner hereinafter to be described.

A magnetic clutch 60 is provided on the shaft 32, which when energized serves to connect the motor 20 directly to the shaft 32 by means of a pulley 61 provided on the shaft 32, a pulley 62 provided on the shaft 17 and a driving element 63 engaged by the pulleys. The purpose of the magnetic clutch 60 is to connect the takeup reel 31 directly to the motor 20 during the starting period of the wire drawing apparatus 14 so that the takeup reel 31 will have the same rate of acceleration as the wire drawing machine 14. After the wire drawing apparatus is brought up to speed by the motor 20, the control apparatus 50 serves to deenergize the magnetic clutch 60, whereupon the variable speed motor 33 is energized and takes over the operation of the takeup reel 31.

The motor 33 is preferably a wound rotor, slipping type of induction motor having suitable resistances and reactances connected in the primary and secondary circuits thereof in such proportions that various input voltages will develop speed-torque curves substantially parallel to each other throughout the selected speed range of the motor 33 from an empty reel to a full reel, as

shown in Fig. 2. In Fig. 2, curve A illustrates a typical speed-torque curve of the motor 33 when a given potential is applied across its primary terminals. The vertical lines marked "Full Reel" and "Empty Reel" illustrate the selected speed-torque range of operation of the motor 33.

It will be noted that the selected operating range of the motor embraces that portion of the curve A in which both the torque and speed are descending. As the winding operation of the wire 21 proceeds from an empty reel to a full reel, the winding diameter of the reel is constantly increasing, therefore, a constantly decreasing motor torque is required. Under theoretically perfect operating conditions, if the motor 33 were operated on curve A, constant tension would be maintained on the wire 21 throughout the takeup operation of the wire from an empty reel to a full reel. But since perfect operating conditions cannot be obtained, due to variable factors such as friction, windage and line voltage, it is necessary to operate the motor alternately on a speed-torque curve B, which is obtained by applying a slightly increased input potential to the motor, and speed-torque curve C, which is obtained by applying a slightly decreased input potential to the motor.

When the motor is operating on curve B, its torque is sufficient to overcome the mass of the pulley and the weight, in which case the speed thereof causes the linear speed of the wire at the takeup reel to exceed the linear speed of the wire at the capstan. Consequently, since the wire is being taken up faster than it is being delivered, the loop formed by the pulley constantly decreases causing the pulley and weight to be raised to their uppermost switch-actuating positions. However, when the motor 33 is operating on the curve C, its torque is not sufficient to overcome the mass of the pulley and the weight, whereupon the speed thereof causes the linear speed of the wire 21 at the reel 31 to be less than the linear speed of the wire at the capstan. In this case the loop formed by the pulleys constantly increases allowing the pulley and weight to descend to their lowermost switch-actuating position. Since the motor 33 is arranged to develop parallel speed-torque curves for different input voltages, the curves B and C, being produced by different input potentials, are parallel to the ideal curve A throughout the operating range of the motor 33. Since the curves B and C are parallel to each other, the changeover from curve B to curve C and vice versa produces a corresponding decrease or increase in the torque of the motor 33. This feature of the motor 33 provides a uniform rising and falling of the pulley 24 and the weight 34 between their switch-actuating limits and prevents any undue jerks on the wire 21 at the time of changeover from curve B to curve C or vice versa.

Fig. 2 also illustrates that many parallel speed-torque curves may be obtained by varying the input potential to the motor. The selection of the ideal operating speed-torque curve for the motor 33, such as the curve A, depends upon the size of the mass of the weight 34 carried by the pulley 24. The weight 34 in turn is selected to exert a constant tension on the wire 21 commensurate with the size of the wire so that the wire will be wound tightly on the reel 31 without causing the wire to pull down in between the convolutions of the previous layer of wire on the reel. Therefore, it is necessary to determine the ideal curve for any given operating condition of wire size and tension exerted by the weight 34, such as curve A, and then adjust the taps of the auto-

transformer 57 so that the motor 33 will operate alternately on speed-torque curves which straddle the ideal curve, such as the speed-torque curves B and C (Fig. 2). The alternate operation of the motor 33 on the curves B and C provides an alternate rising and falling of the weight 34 between their switch-actuating limits, thereby maintaining the fixed tension on the wire 21 even though the torque of the motor is alternately varying between the selected high and low limits determined by the selected curves B and C.

The above-described apparatus operates as follows:

A suitable amount of wire 11 is drawn from the supply reel 10 and threaded through the dies of the wire drawing machine 14. The wire then is passed around the pulleys 22, 24 and 26 to form an adjustable loop and thence to the takeup reel 31. The adjustable loop in the wire 21 is formed so that the weight and pulley supported by the loop assume a position midway of their uppermost and lowermost positions, whereby an intermediate length of wire 21 exists between the capstan 16 and the takeup reel 31. The weight 34, having a known mass sufficient to exert the required tension on the wire 21, to produce a tightly wound reel, is positioned so as to be carried by the pulley 24. Having determined the tension at which the wire is to operate, the proper taps of the transformer 57 are connected to the contactor so that the motor will operate either in the high torque curve B or the low torque curve C. With the weight and pulley in this position, the arms 35 and 36 are positioned so that they pivot 35 downwardly and hold the arm 37 so that the arm 43 of the toggle switch 42 bridges the contacts 45 and 47 of the switch 42. With the wire 11 positioned in this manner, the means provided in the controller 50 for initiating the wire drawing operation is actuated by the operator of the machine.

Upon initiation of the wire drawing operation, the controller 50 simultaneously directs the three-phase potential from a suitable supply (not shown) to the motor 20 and to the autotransformer 57, and also energizes the magnetic clutch 60 so that the motor 20 is driving both the capstan 16 and the takeup reel 31. At the same time, the coil 53 of the contactor 54 is energized by the position of the contact arm 43 of the switch 42, thereby positioning the contacts of the contactor 54 so that a selected voltage is applied to the input terminals of the motor 33 from the autotransformer 57 causing the motor to operate on curve B. Due to the fact that the clutch 60 is energized, the motor 33 is not connected to the shaft 32 but is running, with no load applied thereto.

The wire drawing machine operates in this manner for a predetermined period of time regulated by the controller 50, during which period the wire drawing machine is allowed to come up to full speed operation. Since the magnetic clutch is energized upon the starting of the wire drawing operation, the reel 31 and the capstan 16 are accelerated at the same rate of speed. During this accelerating period, the drive between the motor 20 and the shaft 32 is arranged to produce a peripheral speed of the winding diameter of the reel substantially equal to the peripheral speed of the last step of the capstan 16. Under these operating conditions the pulley 24 and the weight 34 carried thereby remain in their starting positions, and together exert a constant tension on the wire 21 being taken up by the reel 31.

However, when the wire drawing machine 14

is brought up to full speed by the motor 20, it is necessary to vary the speed of the takeup reel 31 in order to compensate for the constantly increasing winding diameter of the reel, which causes the peripheral speed of the reel 31 to exceed that of the capstan 16. Therefore, as soon as the wire drawing machine is operating at full speed, the control apparatus 50 deenergizes the magnetic clutch 60, whereupon the motor 33, which is operating on curve B, takes over and drives the reel 31.

The wire drawing operation continues in this manner, and as the motor is operating on curve B, its torque is sufficient to overcome the mass of the weight and the pulley. Eventually the speed of the wire 21 at the reel exceeds the speed of the wire at the capstan 16. When this occurs, the reel 31 is taking up the wire 21, passing through the adjustable loop formed by the rollers 22, 24, and 26, at a rate faster than the wire 21 is being delivered by the capstan 16.

Since the rate of takeup of the wire 21 is greater than the rate of supply, the adjustable loop is contracted, causing the weight 34 and the pulley 24 to be slowly raised toward their uppermost switch-actuating positions. During the movement of the pulley 24 from its lowermost position to its uppermost position, the pulley 24 and the weight 34 carried thereby exert a constant, predetermined tension on the wire 21, and this tension remains constant even though the torque of the motor 33 is such that the takeup speed of the wire is greater than the delivery speed of the wire.

Continued operation of the wire drawing machine 14 under these conditions will eventually contract the adjustable loop to a point where the weight and pulley will reach their uppermost switch-actuating positions. In so doing, the pulley 24 engages the free end of the arm 36 and moves it upwardly causing the ear 40 of the arm 37 to move downwardly and engage the arm 43 of the switch 42. Continued upward movement of the arm 36 eventually will cause the ear 40 to operate the arm 43 so that it bridges the contacts 44 and 45 of the toggle switch 42.

When the arm 43 is operated in this manner, the coil 53 is deenergized and the coil 52 is energized causing the contacts of the magnetic contactor 54 to be arranged so as to connect a substantial portion of the autotransformer 57 in circuit with the motor 33. By connecting a greater portion of the autotransformer 57 in the circuit to the motor 33, a selected lower voltage is applied across its input terminals, causing the motor 33 to operate on speed-torque curve C (Fig. 2). Since curve C is parallel to the selected speed-torque curve B, a corresponding reduction in torque and speed of the motor is effected by the application of reduced potential to the motor.

With the motor 33 operating on curve C, its torque is not sufficient to overcome the mass of the pulley and weight, whereupon the speed of the reel is reduced so that the speed of the wire at the reel 31 is less than the speed of the wire at the capstan. The wire 21 then is taken up by the reel 31 at a rate less than the rate at which the wire is being delivered to the adjustable loop by the capstan. Under these operating conditions, the loop slowly enlarges and the weight and pulley descend toward their lowermost switch-actuating positions. Throughout the entire downward travel of the pulley and the weight, they exert the same constant tension

on the wire 21, in spite of the fact that the takeup rate of the wire is now less than the delivery rate of the wire. In other words, the changeover in the operation of the motor 33 from curve B to curve C does not affect the tension applied to the wire 21 by the weight and the pulley.

As the motor 33 continues to operate on curve C, the weight and pulley ultimately reach their lowermost switch-actuating positions and actuate the arm 35 downwardly. In so actuating the arm 35, the trip arm 37 is raised so that the ear 40 thereof engages and actuates the arm 43 of the switch 42. Upon such actuation of the arm 43, coil 52 is deenergized, coil 53 is energized and shifts the contacts of the contactor 54 so that the autotransformer 57 delivers an input voltage to the motor 33 which causes it to again operate on curve B. The torque and, consequently, the speed of the motor 33 increases, whereupon the speed of the wire at the takeup reel 31 is greater than the speed of the wire at the capstan 16.

Under this operating condition, the adjustable loop is again contracted and raises the pulley and weight to their upper switch-actuating position. In so doing, the pulley 24 engages the arm 36 and operates the arm 37 which actuates the switch arm 43 and causes the motor to again operate on reduced voltage and the corresponding speed-torque curve C. The operation of the takeup motor 33 continues to alternate back and forth between the upper and lower selected speed-torque curves B and C, respectively, until the takeup reel 31 is full, at which time the wire drawing operation is terminated. The full reel is removed from the shaft 32, an empty reel positioned thereon, and the wire drawing operation is resumed during which the above-described takeup operations are repeated.

It is believed to be apparent from the above-described operation of the apparatus that as long as the weight 34 and the pulley 24 are free to travel between their switch-actuating limits their combined weight exerts a constant tension on the wire 21. The feature of varying the torque of the motor between high and low limits selected in accordance with the wire size and tension to be exerted thereon permits the weight to rise and fall and maintain a constant tension on the wire throughout the takeup operation of the wire from an empty reel to a full reel. By maintaining constant tension on the wire during the takeup operation, a tightly wound reel is obtained, from which the wire may be freely unwound in subsequent processing operations of the wire.

While the above-described apparatus is particularly well adapted to maintain a constant tension on a wire being taken up from a wire drawing machine it may readily be used to maintain constant tension on filamentary strands emerging from various types of continuous strand processing apparatus such as twisting machines, textile insulating machines and continuous vulcanizing machines. Therefore, the scope of the invention is to be limited only by the scope of the appended claims.

What is claimed is:

1. The method of maintaining uniform tension on a strand advancing from a constant speed strand-working apparatus to a strand takeup apparatus, which comprises maintaining a variable supply of strand between the strand-working apparatus and the takeup apparatus, applying a predetermined fixed tension on the portion of the strand in the variable supply, applying a

torque to the strand takeup apparatus sufficient to reduce the variable strand supply to a predetermined minimum limit against the action of the fixed tension on the strand, then applying a torque to the takeup apparatus of such value that the fixed tension on the strand overcomes said torque and increases the variable strand supply to a predetermined maximum limit, and alternately changing the torque applied to the takeup apparatus from one of said values to the other of said values to maintain the variable strand supply within said predetermined limits so that only the fixed tension is applied to the strand throughout the takeup operation from an empty reel to a full reel.

2. The method of maintaining uniform tension on a strand advancing from a constant speed strand-working apparatus to a strand takeup apparatus, which comprises forming a variable loop in the strand between the strand-working apparatus and the takeup apparatus, applying a predetermined fixed tension in the portion of the strand in the variable loop, and alternately taking up the strand with a force sufficient to overcome the fixed tension on the strand and decrease the variable loop by a predetermined amount and taking up the strand with a force which is overcome by the fixed tension on the strand and increases the variable loop by a predetermined amount, whereby only the predetermined fixed tension is applied to the strand as the takeup operation proceeds from an empty reel to a full reel.

3. The method of maintaining uniform tension on a strand being advanced from a constant speed strand-working apparatus to a strand takeup reel driven by a variable speed motor, which comprises forming a variable loop in the path of travel of the strand between the strand-working apparatus and takeup apparatus, supporting a movable weight in the loop to apply a predetermined fixed tension in the strand forming the variable loop, applying a potential to the motor of such value that the resulting motor torque is sufficient to overcome the tension applied to the strand and contract the variable loop to a predetermined limit, then applying a potential to the motor of such value that the fixed tension applied to the strand overcomes the resulting motor torque and enlarges the variable loop to a predetermined maximum limit, and alternately changing the potential applied to the motor from one of said values to the other of said values to reciprocate the weight between said limits so that only the weight tensions the strand as the takeup of the strand proceeds from an empty reel to a full reel.

4. An apparatus for maintaining uniform tension on a strand advancing from a constant speed strand-working apparatus to a strand takeup apparatus, which comprises a takeup reel for receiving the strand from the strand working apparatus, means for forming a variable loop in the path of travel of the strand between the strand-working apparatus and the takeup reel, a weighted pulley riding freely in the adjustable loop for applying a predetermined fixed tension in the strand, means for driving the reel alternately with a force sufficient to overcome the weighted pulley and decrease the variable loop to a predetermined limit and with a force such that the weighted pulley overcomes the force applied to the reel and increases the variable loop to a predetermined limit, and means operable by the weighted pulley for alternately changing the force applied to the reel from one of said

values to the other of said values to maintain the adjustable loop within said predetermined limits so that only the fixed tension applied to the strand by the weighted pulley acts on the strand as the takeup proceeds from an empty reel to a full reel.

5. An apparatus for maintaining uniform tension on a wire advancing from a capstan of a constant speed wire drawing machine, which comprises a reel for taking up the wire emerging from the wire drawing machine, a variable torque motor for driving the takeup reel, a system of pulleys including a freely movable pulley arranged to form a variable loop in the wire between the capstan and the takeup reel, said movable pulley being arranged to freely slide vertically as the length of wire in the variable loop decreases or increase, a weight carried by the movable pulley for applying a predetermined fixed tension on the wire between the wire drawing machine and the takeup reel, means for varying the potential supplied to the motor, and means operable by said movable pulley for actuating the motor potential varying means so that the resulting motor torque maintains the adjustable loop within predetermined limits, said limits being selected so that only the weight applies tension on the strand throughout the takeup operation from an empty reel to a full reel.

6. An apparatus for maintaining uniform tension on a wire emerging from a capstan of a constant speed wire drawing machine, which comprises a takeup reel for taking up the wire emerging from the wire drawing machine, a variable torque motor for driving the takeup reel, said motor having primary and secondary windings arranged to produce parallel speed-torque curves for different input voltages, a takeup reel driven by said motor, a system of pulleys including a freely movable pulley arranged to form a variable loop in the wire between the capstan and the takeup reel, said movable pulley being arranged to slide freely up and down as the length of the wire in the variable loop decreases or increases, a weight carried by the pulley and selected to apply a predetermined tension on the wire, means for varying the potential supplied to the primary terminals of the motor between a potential at which the motor decreases the variable loop to a predetermined minimum limit against the action of weight tensioning the strand and a potential at which the weight increases the variable loop to a predetermined maximum limit against the action of the motor, and a system of levers arranged to be actuated by the movable pulley at each of said limits for actuating the potential varying means so that the motor reciprocates the weight between said predetermined limits, whereby only the weight tensions the strand throughout the takeup of the strand from an empty reel to a full reel.

7. An apparatus for maintaining uniform tension on a strand advancing from a constant speed strand-working apparatus to a strand takeup apparatus, which comprises a takeup reel for receiving the strand, means for maintaining a variable supply of strand between the strand-working apparatus and the takeup reel, means for applying a predetermined fixed tension on the strand in the said variable strand supply to suit the size of the strand, means for taking up the strand on the takeup reel alternately with a torque sufficient to overcome the fixed tension on

11

the strand and decrease the variable strand supply to a predetermined limit and with a torque which is overcome by the fixed tension on the strand so that the variable strand supply increases to a predetermined limit, and means responsive to the size of the variable strand supply for alternately varying the torque applied to the takeup reel to maintain the variable strand supply within said predetermined limits so that only the predetermined fixed tension acts on the strand throughout the takeup of the strand from an empty reel to a full reel.

8. The method of maintaining uniform tension on a strand advancing at a constant speed to strand takeup apparatus, which comprises forming a variable loop in the path of travel of the strand, supporting a freely movable weight in the loop to apply a predetermined fixed tension on the strand, taking up the strand with a force sufficient to move the weight in one direction until it engages a predetermined limit, then taking up the strand with a force sufficient to move the weight in the opposite direction until it engages a second limit, and alternately changing the takeup force applied to the strand from one of said values to the other of said values so that only the weight tensions the strand as it is taken up by the takeup apparatus.

9. An apparatus for maintaining uniform tension on a strand advancing at constant speed to strand takeup apparatus, which comprises a system of pulleys including a freely movable pulley for forming a variable loop in the strand advancing to the takeup apparatus, a weight

12

supported by the pulley for applying a predetermined fixed tension on the strand, adjustable means for taking up the strand with a force sufficient to move the pulley and weight in one direction and reduce the variable loop, means engaged by the pulley when the loop decreases to a predetermined limit for changing the force applied to the takeup means to such a value that the pulley and weight move in an opposite direction and increase the variable loop, and means engaged by the pulley when the loop increases to a predetermined limit for changing the takeup force so that the pulley and weight move in the first-mentioned direction, whereby the weight maintains uniform tension on the strand throughout the takeup operation from an empty reel to a full reel.
